UNITED STATES PATENT OFFICE.

THOMAS M. LAHEY, OF BROOKLYN, NEW YORK.

DESIGN FOR A BOTTLE.

SPECIFICATION forming part of Design No. 11,864, dated July 13, 1880.

Application filed June 3, 1880. Term of patent 3½ years.

To all whom it may concern:

Be it known that I, THOMAS M. LAHEY, of Brooklyn, in the county of Kings and State of New York, have invented a new and Improved Design for Bottles, of which the following is a specification.

Figure 1 is a perspective view of the bottle. Fig. 2 is a plan of the bottom thereof.

The design will first be described in connection with the drawings, and then pointed out in the claim.

In the drawings, A A represent the two ribbed sides of the bottle, provided with ribs a a. B represents the plain side of the bottle.

C is the screw-thread formed on the neck of the bottle, and D indicates the word "Poison," stamped on its sides A A B.

Having thus fully described my invention, I claim as new and desire to secure by Letters Patent—

The design for a bottle herein shown and described, the same consisting of the triangular pyramidal shape, the ribbed sides A A, and the plain side B.

THOMAS M. LAHEY.
